UNITED STATES PATENT OFFICE

MARK N. RUSSELL, OF SYRACUSE, NEW YORK, ASSIGNOR TO PASS & SEYMOUR, INC., OF SYRACUSE, NEW YORK, A CORPORATION OF NEW YORK

ELECTRIC FIXTURE

Application filed August 26, 1927. Serial No. 215,721.

This invention relates to convenience outlets and more particularly to convenience outlets for mounting in the canopies of electric light fixtures.

5 It is a general object of the present invention to provide a novel and improved form of convenience outlet.

More particularly it is an object of the invention to provide a convenience outlet arranged to have a minimum depth in order 10 that the same may be used in very shallow canopies.

A further object of the invention consists in the provision of a simple block of insulating material adapted to be secured to the rear face of a canopy, or a portion thereon which is formed of insulating material, provided with plug blade openings, said block having recesses to receive contact springs 15 which are freely retained therein by the walls of the recesses and the engaging face of the insulating portion of the canopy.

A still further object of the invention consists in the use of bowed contacts whose 20 major axes are arranged transversely to the line of movement of the plug blades and which contacts are not rigidly secured to the insulating parts of the convenience outlet.

Other and further objects and features of 25 the invention will be more fully apparent from the accompanying drawing and following specification wherein is disclosed a single exemplary embodiment of the invention, it being understood, however, that various 30 changes may be made therein such as fall with the scope of the appended claims without departing from the spirit of the invention.

In said drawing:

40 Fig. 1 is the front elevation of a lighting bracket provided with the device of the present invention;

Fig. 2 is a vertical section through the same on line 2—2 of Fig. 1;

45 Fig. 3 is a rear elevational view thereof;

Fig. 4 is a horizontal section taken on line 4—4 of Fig. 1;

Fig. 5 is a face view of the insulating contact receiving block showing the contacts in 50 place; and

Fig. 6 is a perspective view of one of the contacts and its terminal wire.

When attempting to mount convenience outlets in fixture canopies, for instance such as those formed of porcelain or the like insulating material and intended for use in 55 kitchens, laundries, baths and similar places, difficulty has been experienced, heretofore, where the canopies were extremely shallow, since the well-known forms of convenience 60 outlets are provided with spring contacts of considerable length and whose major axes extend in the direction of movement of the plug blade. These contacts are fastened to suitable insulating supporting means below 65 the innermost end of the plug blades and thus require too great a depth for use in shallow canopies. The present invention contemplates an arrangement which extremely simplifies the previous constructions and which 70 makes use of contact springs arranged transversely of the line of movement of the plug blades and which are not fastened to their insulating support.

Referring to said drawing it will be seen 75 that the invention has been illustrated, for convenience, in connection with a wall bracket which includes the canopy 10, here shown as of circular configuration, provided near the periphery with the opening 11 80 through which the screw shell 12 of a suitable lamp receptacle 13, may be passed to receive onto its external threads, the shade ring 14. The receptacle 13 fits against a shoulder 15 and is thus held in place on the canopy between this shoulder and the shade ring. 85

A suitable aperture 16 in the center of the canopy allows for the passage of fastening means to secure the canopy to a wall or other surface. 90

The canopy is preferably provided with a recess 17 in the back thereof in order to provide room for wiring. The front wall 18 of the canopy is quite thick and in the present instance is formed of insulating material although it is obvious that such is not required, provided there is an insulating insert where the blades of the attachment plug must pass through the same. In the present instance the boss 19 on the face of the canopy is in- 95 100

tegral therewith and is of suitable diameter to be in accord with the diameter of an attachment plug. It is provided with the usual plug blade openings 20 which pass from the 5 front face into the recess 21 opening into the back wall of the canopy. This recess is adapted to house and position the insulating block 22 which is shown to be of substantially the same thickness as the depth of the 10 recess and to be of the same non-circular configuration as the recess so that a single fastening means, such as the screw 23 and nut 24, is sufficient to hold it in position with its front face 25 against the bottom wall 26 of the 15 recess 21.

The block 22 is provided with two recesses 27 which open into the front face 25 thereof. Each recess is arranged to be in communication with one of the openings 20 and has at 20 its bottom what may be construed as an extension of such opening. The distance from the front face of the boss 19 to the bottom of these extensions 28 is at least as great as the length of the blade of a normal attachment 25 plug. The major portion of the recess 27 is considerably wider than the thickness of a plug blade and the sides thereof are parallel. At one end of the recess is a diagonal wall 29 on the inner side and at the opposite end 30 both sides of the recess flare as shown at 30. Adjacent these flaring walls is the flat end wall 31.

Arranged within each recess and freely contained therein is a spring contact member 32 35 formed of a strip of conducting material of a normal width slightly less than the main depth of the recess 27. The contact is bowed to a convex form by bending transverse to its longitudinal axis. This arrangement allows the ends 33 and 34 to lie near to the outer wall of the recess 27 while the central portion 35 of the contact is bowed away from the wall and lies directly beneath the center of the opening 20. A guide lug 36 extends from 40 the center of the upper edge of the contact and is bent so that its outer end lies substantially in the same plane as the ends 33 and 34 of the contact. It will be seen from Figure 4 that this guide lug lies in an enlargement 37 45 of the opening 20 and serves to guide the plug blade onto the convex face of the spring to cause the same to be flattened and thus exert pressure against the side face of the blade. The narrow end of the recess caused 50 by the diagonal wall 29 serves to more readily position the contact spring and to hold the punched-up portion 40 thereof out of engagement with the opposite wall of the recess. This portion 40 by engagement with the wall 55 of a hole in the plug blade prevents its accidental removal as is well known.

Adjacent the end 34 of the spring it is bent at a right angle to the plane of the two ends to form the portion 41 which fits in the 60 widened end of the recess. To this wing por-

tion may be soldered a terminal wire 42 preferably by passing the same through an opening in the wing and applying a drop of solder on the wire and the inner side of the wing. It may sometimes be desirable to thread a circular washer 43 over the conductor wire before soldering the same to the part 41, in which case a suitable enlargement of the end of the recess 27 to receive this washer must be provided as clearly shown in Figure 5. This washer holds the contact as shown in Fig. 5. 70

Each terminal or conductor wire passes through a groove 45 in the end of the block 22 and passes through the channel 46 into the recess 17 in the back of the canopy. The groove 45 is preferably slightly less in width than the normal diameter of the insulating covering on the conductor wire so that a tight fit for this wire is provided. This serves to hold the conductor wire and the contact in 80 position in the block for convenience in assembling the same in the canopy. 85

When the block is assembled in the recess in the canopy the upper edge of the contact is preferably just out of engagement with the bottom wall of the recess in the canopy so that the contact is free to be bent by the plug blade and it may be said to be freely mounted within the recess transversely to the line of movement of the plug blade thus reducing 95 very materially the depth of the whole convenience outlet. The contact member is partly positioned in the recess by its configuration and partly by the terminal wire secured thereto. 100

Having thus described the invention, what is claimed as new and desired to be secured by Letters Patent is:

1. In a convenience outlet, the combination with a fixed supporting means having plug blade openings, of an insulating block secured to said supporting means and having a recess for and in communication with each opening and a spring contact loosely arranged and fully housed in each recess with its longitudinal axis extending at right angles to the line of movement of a plug blade and with its greatest width less than the distance a plug blade extends into said recess. 105

2. In a convenience outlet in combination with an insulating support having a plug blade opening, a block of insulating material having an elongated recess therein in communication with said opening, a bowed contact loosely arranged in said recess and having its ends adapted to be pressed against a side wall thereof and its center beneath said opening with the convex side positioned to engage said blade. 110

3. In a convenience outlet in combination with an insulating support having a plug blade opening therethru, a block of insulating material having an elongated recess in one face thereof adapted to communicate with said opening when said block is secured to said 120 125 130

support, a bowed contact loosely arranged in said recess with its ends adapted to be pressed against a side wall thereof, a wing on one end of said contact abutting an end wall of said recess and a conductor wire secured to said wing and passing thru said end wall.

4. In a wall bracket, in combination, a canopy of insulating material having a recess in the inner wall thereof, a block of insulating material in said recess having contact receiving recesses therein and contacts retained entirely in said recesses by engagement with the bottom wall of said canopy recess.

5. In a wall bracket, in combination, a canopy of insulating material having a depression in the inner wall thereof connected to the outer wall by plug blade openings, a block of insulating material received in said depression and positioned by the walls thereof, recesses in the front face of said block, a contact in each recess beneath an opening, each contact being freely mounted in its recess and retained in position by the bottom wall of said depression, each contact being arranged transversely to the line of movement of the plug blade and being of less width in that direction than the length of plug blade normally extending into the contact recess.

6. As an article of manufacture, in combination, an integral contact spring for a convenience outlet formed from an elongated strip of metal having its center portion bowed out of the plane of the ends, a guide lug extending from substantially the center of one of the long sides of the strip and bent slightly toward the plane of the end portions, a wing at one end of the said strip at substantially right angles to said plane, and an insulated conductor wire soldered to the wing and extending away from the contact at substantially a right angle to the face of said wing.

45 In testimony whereof I hereunto affix my signature.

MARK N. RUSSELL.
